UNITED STATES PATENT OFFICE.

ARTHUR MELVIN LEIGHTON, OF PORT TOWNSEND, WASHINGTON TERRITORY, ASSIGNOR OF ONE-HALF TO JAMES HOMER LIVERMORE, OF SAME PLACE.

ADJUSTABLE LAST.

SPECIFICATION forming part of Letters Patent No. 407,080, dated July 16, 1889.

Application filed January 17, 1889. Serial No. 296,773. (No model.)

To all whom it may concern:

Be it known that I, ARTHUR MELVIN LEIGHTON, of Port Townsend, Jefferson county, Washington Territory, have invented a new and useful Improvement in Adjustable Lasts; and I do hereby declare the following to be a full, clear, and exact description of the same.

My invention consists in a new and improved adjustable cobbler's last which can be readily adjusted to closely fit any size of boot or shoe, no matter whether the boot or shoe has a pointed or a wide toe, and my invention will be hereinafter fully described and claimed.

Referring to the accompanying drawings, Figure 1 is a top perspective view of my invention, showing the pointed end of the toe part of the last adjusted in front. Fig. 2 is a top plan view showing the broad end of the toe part adjusted in front. Fig. 3 is a longitudinal vertical central sectional view of the entire last, and Fig. 4 is a detail view of the hinge which connects the two parts of the last.

The same letters of reference indicate corresponding parts in all the figures.

Referring to the several parts by letter, A indicates the toe part of the last, and B the heel and instep part, the last being preferably constructed of malleable iron. The heel part B is formed with a longitudinal opening C, coming out under the instep, the rear end of this hole at the back of the heel being filled with a tightly-fitting wooden plug B', the object of this plug being to enable the cobbler to tack and hold the last in place in the boot or shoe. The instep of the heel part B has formed on top of it a longitudinal recess or groove E, and near the lower end of this recess is formed a threaded aperture F, in which fits the lower end of a thumb-screw H, having a flattened head, as shown.

The toe part A of the last is made pointed at one end to fit a pointed-toed shoe or boot, and wide at the other end to fit a wide-toed shoe or boot, and is curved or arched upward from the center to each end, as shown, being convex on the lower side and of uniform thickness, preferably, and beveled around the upper edge. The toe part is formed at

its center in its upper concave side with a smooth-bored circular recess I about three-fourths of an inch in diameter, and in depth about one-third of the thickness of the toe part. The short front part of the hinge is 55 formed on its lower side with a circular projection or shoulder J, which fits exactly in the opening I.

Directly opposite the recess I is formed in the lower side of the toe part a circular recess K of the same size as the upper recess I, and in this lower recess fits a steel nut L, the lower side of which is flush with the concave bottom of the toe part, while the center of the nut is formed with an upwardly-extending collar L', which passes up through a central opening M in the wall which divides the upper and lower recesses, forming a steel bearing on which the projection J of the hinge turns, a screw N passing up through 60 the center of the steel bearing-nut L into the center of the hinge projection J, as shown clearly in Fig. 3. The upper or rear hinge-strap O fits in the longitudinal recess E and is formed with a central longitudinal slot O'. 65 The flattened head of the thumb-screw H passes up through this slot, and it will be seen that by tightening this thumb-screw the slotted hinge-strap will be held firmly at any point at which it is adjusted in the recess E. 70

The upper face of strap O is marked with a scale P, so that the last can be readily lengthened or shortened to fit any size of shoe or boot by means of the slotted strap and thumb-screw. 75

By constructing the lower end of the hinge and the toe part as shown and described it will be seen that the toe part can be turned around, so as to use either the sharp-pointed or wide end, as required. By hinging the 80 lower and upper parts of the strap together at G, I am enabled to bend the last at the center for convenience in inserting it in a shoe or boot, while when in position the rear end of the toe part will extend beneath the 85 end of the instep, as shown.

From the foregoing description, taken in connection with the accompanying drawings, the construction and advantages of my invention will be readily understood. It will 90

be seen that my adjustable last is very strong and simple in construction and that the one last can be readily and easily adjusted in a moment to fit any boot or shoe.

5 Having thus described my invention, what I claim, and desire to secure by Letters Patent, is—

1. The combination of a heel part formed with the longitudinal recess, a double-pointed toe part, a hinge pivotally secured at one end to the toe part and having its other end formed with a longitudinal slot, and the retaining-screw, substantially as set forth.

2. In a last, the combination of the heel part formed with the longitudinal recess, the reversible curved toe part formed with a narrow end and a wide end and having the central circular recesses and opening, the lower nut having the central bearing-collar, the con-

necting-screw, the hinge having the circular projection formed with the central threaded aperture on its forward end, and the rear strap formed with the longitudinal slot, and the thumb-screw, substantially as set forth.

3. In a last, the combination of the heel part formed with the longitudinal recess, the threaded aperture, and the heel-opening having the plug in its rear end, the toe part having a narrow end and a wide end, the hinge pivotally secured at one end to the toe part and having its other end formed with a longitudinal slot, and the thumb-screw, substantially as set forth.

ARTHUR MELVIN LEIGHTON.
